FAUCET

Gordon L. Hall, Old Lyme, Conn.

Application January 20, 1950, Serial No. 7,369

Term of patent 14 years

(Cl. D91—3)

To all whom it may concern:

Be it known that I, Gordon L. Hall, a citizen of the United States of America, residing in Old Lyme, in the county of New London, State of Connecticut, have invented a new, original, and ornamental Design for a Faucet, of which the following is a specification, reference being had to the accompanying drawing, forming a part thereof, wherein:

Figure 1 is a plan view of the faucet showing my new design;

Figure 2 is a front view in elevation of the faucet illustrated in Figure 1; and,

Figure 3 is a side view, in elevation, of the faucet illustrated in Figure 1.

The rear, not shown, is substantially like the front shown.

I claim:

The ornamental design for a faucet, substantially as shown and described.

GORDON L. HALL.
